E. DUNSHEE

QUADRUPED WALKING MECHANISM

Filed May 3, 1924

EEG I

Inventor;
Earl Dunshee,
per W. W. Crandall
Attorney.

UNITED STATES PATENT OFFICE.

EARL DUNSHEE, OF LOS ANGELES, CALIFORNIA.

QUADRUPED-WALKING MECHANISM.

Application filed May 3, 1924. Serial No. 710,907.

To all whom it may concern:

Be it known that I, EARL DUNSHEE, a citizen of the United States, residing at Los Angeles, in the county of Los Angeles and State of California, have invented a new and useful Quadruped-Walking Mechanism, of which a specification is set forth below.

In this specification, and the accompanying drawing, I shall describe and show a preferred form of my invention, and specifically mention certain of its more important objects. I do not limit myself to the forms disclosed, since various changes and adaptations may be made therein without departing from the essence of my invention as hereinafter claimed; and objects and advantages, other than those specifically mentioned, are included within its scope.

My invention relates to mechanism for simulating the walking and running motions of quadrupeds, and among its salient objects are: first, to produce a mechanism of this kind that is well adapted for animated toys; second, to provide means whereby various gaits such as trotting, running, single-foot, etc., may be closely imitated in a device of this nature; third, to furnish convenient means for altering or adjusting the gait to suit the requirements; and, fourth, to accomplish the above in a very simple and relatively inexpensive construction.

My objects are attained in the manner illustrated in the accompanying drawing, in which—

Figure 1 is a side elevation of the complete mechanism; and Figure 2 is a plan view of the same.

Similar reference numerals refer to similar parts throughout both views.

In the form of my invention selected for illustrative purposes, I employ any suitable clockwork driving mechanism, self-contained between side plates 3 and 4, which are spaced by cross struts 5 to which the plates are attached by screws 6. Such a mechanism as shown is driven by a spiral spring 7, wound up in the usual manner by ratchet 8 and key post 9. The spring power drives the main operating shaft 10 through suitable multiplying gearing, and the shaft carries a double throw overhung crank at each of its extremities as shown in Figure 2.

As a usual thing the two cranks at either end of the operating shaft are not diametrically opposed; and the two cranks at one

end of the shaft are not in the same angular position as the cranks at the other end. The angular relation of the two cranks of each pair, as well as the angular relation of the pairs with respect to each other, largely determines the resulting gait of the mechanism.

A pair of upright stanchions 11, spaced by struts 12, are pivoted to the side plates at 13, and may be vertically positioned at various angles by means of screws 14 and tapped holes 15. This positioning also effects the gait of the mechanism.

The walking mechanism proper comprises four bell-crank levers 16 pivoted at their apexes 17 to links 18, which in turn are pivoted at 19 to the top end of stanchions 11. One arm of each of these levers is operatively connected to one of the cranks 20 on the operating shaft. The other serves as a walking leg of the mechanism, and the weight of the latter rests wholly upon the extremities of either two or three of these legs at all times.

In the mechanism described the lower extremities of the legs, corresponding to the feet of a quadruped, describe elongated closed curves when the operating shaft is rotated. Assuming the proportions and angular adjustments illustrated in the drawing, the lower extremities of the legs actually move in the narrow elliptical paths 21. These are nearly, but not quite, parallel with the ground. They are drawn, of course, in relation to the mechanism and do not represent the movement of the feet with respect to the ground. The lower portion of the path represents the time that the foot is either approaching or in contact with the ground. The upper portion represents the time that the foot has been lifted and is being returned to its forward position.

As illustrated the weight of the mechanism is momentarily borne by forward near foot 22 and rear far foot 23. Both of these are relatively moving rearward to the right and give the mechanism an absolute forward motion to the left. Feet 24 and 25 are raised above the ground and relatively are moving forward to the left. Crank shaft 10 is being turned left handedly, or counter-clockwise in this case.

As indicated above, the paths 21 may be given various shapes, by varying the angular relation of the cooperating parts, to produce a variety of gaits. Stanchions 11 are variably positioned for this purpose by screws

14 and tapped holes 15. The two cranks 20 of either pair may have their angular relation changed by twisting, or by bending the outer arm. This also results in changing the throw of the outer crank. The two crank pairs may have their angular relation changed by giving the intermediate portion of operating shaft 10 a slight twist. Obviously many varieties of gaits may be obtained in this manner.

Before passing on it is to be noted that the feet of each side of the mechanism always move in opposite directions, as is the case in most gaits of normal animals. It is also to be noted that the two feet in contact with the ground are always moving in the same direction, and that these feet are diagonally opposite.

For giving a wagging motion to the tail and head of an animal to be simulated I use light levers 26, intermediately pivoted at 27 to ears 28 turned over from the top of side plate 4. The inner ends of these levers are bifurcated, and engage the periphery of a wave shaped disk 29 mounted upon driving shaft 30, or upon any other convenient rotating shaft of the mechanism. The outer ends of levers 26 may be bent upwardly, as shown in Figure 1, to attach to a pivoted head or tail.

The parts 31 shown in Figure 2 are merely

cylindrical spacers. Bell-crank levers 16 ordinarily should have angles of less than 90 degrees and their apexes 17 should be above operating shaft 10 in most cases.

35

For simulating an animal, a skin or fur is mounted upon a suitably shaped shell to which the head and tail are pivoted. This shell may be attached to struts 12, or any other fixed part of the construction, and the outer ends of levers 26 are then operatively connected to the head and tail. The feet may be shaped to imitate hoofs or paws, and the legs may be covered with fur.

Having thus fully described my invention, I claim:

Quadruped walking mechanism comprising; a frame; a link pivotally suspended from each corner of the frame; a bell-crank lever pivotally suspended at its apex from the free end of each link; a four-throw crank shaft; and a power source adapted to rotate said shaft; one of the arms of each of said levers being separately engaged by a crank of said shaft, and the other arm being adapted to act as a walking leg; the crank throws being arranged in non-diametrically opposed pairs at each side of the mechanism and so disposed that the corresponding lever legs on the respective sides may be oscillated oppositely.

EARL DUNSHEE.
